GAME

Raffaele Morelli, Brooklyn, N. Y.

Application April 20, 1944, Serial No. 531,950

3 Claims. (Cl. 273—105.2)

This invention relates to games, and has among its objects the provision of a device of the character described particularly adapted for target practise and having improved means whereby various hazards are provided for testing the concentration of the player as well as his sharp shooting ability.

More particularly, it is among the objects of the invention to provide improved means providing not only a moving target, but one which disappears almost the instant that it is presented in proper target position, and one whose rate of motion must be gauged with a high degree of accuracy; improved means whereby a series of targets move to and fro along a member providing a path and in so doing disturb the member to thereby increase the mental hazard at the target; and improved means whereby the several targets are movable while traveling along their path to thereby distract attention and increase the hazard in respect to the target that approaches the firing position.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a fragmentary view in front elevation with parts removed and in section showing a device embodying the invention.

Fig. 2 is a fragmentary view in side elevation with parts removed and in sections.

The advantages of the invention as here outlined are best realized when all of its features and instrumentalities are combined, but, useful embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 10 denotes a device embodying the invention. The same may include a rotary means such as a disc 11 mounted on a shaft 12 that may be driven by any suitable motor or power source 13, the speed of which has

been sufficiently reduced for its intended purpose. Formed in the disc 11 near its periphery is an annular series of circular ball receiving openings or cavities 14, equally angularly spaced from each other. At the front side of the disc are holes 15 coaxial and communicating with their respective cavities 14. From each of the latter extends a short opening or passage 16 to the rear face of the disc 11, these passages 16 thus forming a rearwardly divergent series. Accordingly, a lowermost opening 16 slopes rearwardly and downwardly, and an uppermost opening 16 slopes frontward and downwardly. Except for these uppermost and lowermost openings 16, all others of these openings are closed by a stationary disc-like plate 17 carried by any supports 18, 19. In other words the plate 17 lies in sliding contact with the rotary disc 11 and is provided with openings 20 lying in a vertical central plane and being adapted to align with the uppermost and lowermost openings, the plate 17 also having a central opening through which the shaft 12 may pass freely. Extending from the cavities 14 are the generally spiral passages 21, each terminating in a closed ended portion 21a in relative proximity to the shaft 12. Thus the closed ended portions 21a form an annular series coaxial with the disc 11, with the cavities 14 and with the openings 15. These portions 21a are equally angularly spaced apart, and with the disc 11 moving clockwise the portions 21a are angularly rearward or offset relative to their respective cavities 14, the passages 21 thus forming acute angles with lines radial to their respective cavities 14. By reason of the close spacing involved, the passages 21 are curved so as to clear adjacent passages without intersecting the same. It will now be seen that all the various details of the disc 11 as described form a wholly uniform symmetrical structure which is neat and lends itself to inexpensive manufacture as by making the same of two disc-like halves and securing the same together along a central plane at right angles to the shaft 12. Accordingly, the disc 11 may be made of plastic, preferably in a transparent form, such as Lucite, for a reason hereinafter apparent. Within the various parts of the passages 16 and 21 and through the openings 20 of the plate 17 are movable the balls or targets 22, these being actuated mainly gravitationally, except as otherwise described. Hence many movements are accomplished with little operating mechanism.

In the drawing are shown five balls 22, although any desired number may be used. Three of these balls are in an upper position in the disc 11, and

one is in a lower position therein. A fifth ball has dropped out gravitationally from the lowermost cavity 14 due to the slope of passage 16. A suitable means is provided to return the last mentioned ball to an uppermost cavity 14, which is the primary or firing position for the target. The means referred to may include an endless conveyor which may comprise a chain or belt 23 trained around a driver pulley 24 and an idler pulley 25 mounted on shafts journaled in stationary brackets or bearings 26, the drive pulley having its shaft 27 engaged by any speed change means 28 driven by the power source 13. Preferably, the shaft 27 turns counterclockwise while the shaft 12 turns clockwise, the speed ratio being made to suit as hereinafter apparent. It is noted that the axes of the pulleys 24, 25 are inclined, so that the belt 22 is at an acute angle to the vertical for a purpose later described. An idler pulley 29 on the shaft 12 is utilized to function as a spacer for one run of the belt for proper operation of the conveyor.

Carried by the belt 22 are three or more bucket-like elements 30, each formed like a short, generally horizontal tube. For mounting the elements on the belt, rods 31 may be affixed to the belt at the outer face thereof, the elements being connected to the rods in any suitable manner to permit the elements to tilt from the lower horizontal position of Fig. 2 to the inclined uppermost position shown. A simple means may include an arm 32 connected to its rod 31 at an adjustable angle as by a universal ball and socket connection 33, the other end of the arm being pivotally connected to its element as at 34. The significant details about the elements 30 are that they are open ended, the edge 35 nearest the plate 17 being beveled or cut along a plane oblique to the axis of the element, its opposite end having a bottom internal projection or shoulder 36. The element 30 lies normally gravitationally horizontal, and may be thus even when it receives a ball 22, as the latter may lie so close to the point of suspension as not to overcome the gravitational balance. In its lowermost position as in Fig. 2, the lower edge of the inclined or beveled face 35 is in sliding contact with the plate 17. Here, although the element is horizontal, the inside surface 37 of the bottom wall is inclined downwardly and rightward from the disc 11 so as to align with the adjacent passage 16 to permit a ball 22 to roll from the latter smoothly into the adjacent element 30. If it is preferred that the ball when resting against the stop 36 shall lie slightly rightward of the point of suspension, then clockwise swinging of the carrier 30 may be prevented by its lower edge abutment against the plate 17 or by causing the pivotal connection 34 to have a stop action in any well known manner. As the lower carrier 30 is carried upward by the belt 22 it approaches the plate 17 ever more closely, and hence the plate 17 causes pressure against the carrier 30 to tilt or swing the same counterclockwise about its pivot 34 until the entire edge 35 is in contact with the plate 17 and the carrier in alignment with an uppermost cavity 14 through an opening 20 in the plate to thus discharge the ball 22 that has been conveyed upward. In intermediate positions the ball will not fall out, as the carrier is closed by the plate 17, nor will the carrier tilt to permit the ball to drop out since the inclination at 37 may be rather slight. Further, the pivot at 34 may be a spring device tending to yieldingly resist such counterclockwise movement. By reason of the idler 29, the carriers

30 are spaced away and will not impinge on shaft 12. The speed of the shaft 27 is such that when a carrier moves from the lowermost to the uppermost positions shown in Fig. 2, the disc 11 moves through an angle of 45 degrees to bring the cavities 14 into successive register with the carriers 30.

In operation, as the disc member 11 rotates, balls 22 successively fall from closed ended portions 21a of the passages 21 to the cavities 14 at the outer ends thereof. This drop of a ball from A to B imparts an impulse to the disc member, causing a sudden jerk-like motion. As rotation continues, the ball moves from position B to position C at which it is free to pass through opening 20 in disc 11 to enter the lower carrier 30. When the latter attains its upper position in Fig. 2, the ball drops through opening 20 into the uppermost cavity at position D and rolls downward in a passage 21 to a position as at A, in readiness to repeat the cycle. During the upward travel of a carrier 30, the disc 11 is turning so that when the carrier reaches its upper discharging position, a cavity 14 has moved into alignment therewith.

When a ball 22 is at D, a position which it occupies only for an instant, the player fires at it, and if the projectile passing through a hole 15 strikes the ball, the latter will be thrown rearward over the shoulder 36 and hence out of the carrier 30. This is facilitated by the length of the rods 31 whereby the belt is amply spaced from the disc 11; also the adjacent run of the belt is lateral to the center of the cavity at D, because of the angle caused by the idler pulley 29. If the bullet fails to hit the ball squarely, the ball may not be discharged and hence will roll down passage 21 to position A. The player who eliminates all the balls with the fewest shots wins the game. The hazards of the game may be increased by the dropping of balls in passages 21 causing a jerky movement, which may be permitted by ample backlash clearance in the gears of the drive or power source at 13. Also, if the disc 11 is translucent, the player's attention tends to be distracted by rotational movement of other balls, and this may be realized through holes 15, even if the disc be not translucent. Thus the player's concentration is tested and hazards are introduced to indicate how steady he is in his play.

The device 10 is simple and cheap and avoids the need of placing the balls manually, as where a near miss or glancing impact might otherwise cause the ball to fall out of position. It requires very little power to operate because of the balanced arrangement of the disc and the disposition and movement of the balls.

I claim:

1. A device including a generally circular member, horizontal means for rotatably mounting the same, the member having a series of angular passages therein each of which is at an angle to the radius of the member, each passage having one closed end in relative proximity to the axis of the member, the member having passages transverse to the angular passages and each of the latter terminating at its outer end in a transverse passage, the transverse passages being open at the rear side of the member and having restricted aligned holes at the front side of the member, balls in said passages, and a stationary plate at the rear side of the member closing the transverse passages but having top and bottom openings aligned with those transverse passages which mo-

mentarily move into a position where they lie along a vertical plane, said transverse passages forming a series tapered toward the front side of the member, and conveyor means for receiving a ball from the lower transverse passage that is aligned with a bottom opening in the plate and for carrying the same upward and discharging the ball into a transverse passage that is in alignment with the top opening of the plate.

2. A device according to claim 1 wherein the conveyor means includes an endless conveyor having a belt lying in a plane at an acute angle to the plane of the member, carrier elements and means pivotally mounting the carrier elements on the belt, each carrier element being of open-ended tubular form and each tending to assume a generally horizontal position, each carrier element having means whereby it tends to lie in alignment with transverse passages at the top and bottom openings in the plate so that a ball rolls through the bottom opening of the plate into a carrier element and from a carrier element through the top opening of the plate, each carrier element having its end nearest to the plate at an angle to cause the plate to tilt the element into

alignment with a transverse passage at the top opening and being normally in aligned relation to a transverse passage at the bottom opening, said tilting movement occurring as the belt moves the pivotal means toward the plate, and each carrier element having means to prevent a ball from rolling out of the element in a direction away from the plate while permitting such removal of the ball from the element above the last mentioned means.

3. A device according to claim 1 wherein the conveyor means includes carrier means adapted to align with a transverse passage at the bottom opening so that a ball may roll into the carrier means, and means whereby the latter is moved upward and tilted to align with a transverse passage at the top opening so that the ball can roll from the carrier means into said transverse passage, the carrier means being so open that a projectile striking a ball through a restricted opening is adapted to hurl the ball out of the carrier means to prevent the ball from entering said passage.
